UNITED STATES PATENT OFFICE

150,522

DESIGN FOR A WASH FOUNTAIN

Clifford Brooks Stevens, Milwaukee, Wis., assignor
to Bradley Washfountain Co., Milwaukee, Wis.,
a corporation of Wisconsin

Application April 23, 1947, Serial No. 138,568

Term of patent 14 years

(Cl. D4—2)

To all whom it may concern:

Be it known that I, Clifford Brooks Stevens, a citizen of the United States of America and residing at Milwaukee, in the county of Milwaukee and State of Wisconsin, have invented a new, original, and ornamental Design for a Wash Fountain, of which the following is a specification, reference being had to the accompanying drawing, forming a part thereof.

In the drawing,

Fig. 1 is a plan view of a wash fountain, showing my new design.

Fig. 2 is a front elevational view of my new design, and

Fig. 3 is a side elevational view of my new design.

I claim:

The ornamental design for a wash fountain, as shown.

CLIFFORD BROOKS STEVENS.
